UNITED STATES PATENT OFFICE

112,985

DESIGN FOR A STATUETTE OR SIMILAR ARTICLE

Roger Noble Burnham, Los Angeles, Calif.

Application June 10, 1938, Serial No. 77,712

Term of patent 3½ years

To all whom it may concern:

Be it known that I, Roger Noble Burnham, a citizen of the United States, residing at Los Angeles, in the county of Los Angeles and State of California, have invented a new, original, and ornamental Design for a Statuette or Similar Article, of which the following is a specification, reference being had to the accompanying drawing, forming part thereof.

I claim:

The ornamental design for a statuette or similar article as shown.

ROGER NOBLE BURNHAM.
